DEVICE FOR KEEPING COUNT OF TELEPHONE CALLS

Filed April 30, 1930

UNITED STATES PATENT OFFICE

JOSEPH J. SHERIDAN, OF PHILADELPHIA, PENNSYLVANIA

DEVICE FOR KEEPING COUNT OF TELEPHONE CALLS

Application filed April 30, 1930. Serial No. 448,680.

The present invention relates to an improved device for keeping count of telephone calls, as each call is made, the device to be carried in close position on the mouth piece 5 of a telephone transmitter, so that when a call is completed, the party making the call may manually move an index element on a disc or the device, so that one part of the index element may cover a number, showing that another call has been added to the previous list. In this manner the number of calls made over a telephone may be counted.

One of the purposes of the invention is to provide a device of this kind consisting of a 15 disc of any suitable material such as pressed paper pulp, while celluloid, bakelite, paralyn, or similar material, or possibly aluminum, may be used, having on one face an annular shoulder or rib adjacent the margin of the 20 disc, and on either or both faces space for advertising matter, the face opposite the rib or shoulder having numbers in consecutive order from 1 to 50, with a clip constructed from one piece of material, such as sheet metal 25 or the like, possibly paralyn or celluloid or similar substance, so constructed and formed as to engage with the margin of the disc and overlie the rib or shoulder and engage thereunder in suchwise as to assist materially in 30 retaining the clip in various positions when adjusted, the clip having a suitable projection in order to be clasped so that it can be moved along the margin of the disc.

Another purpose is to provide, in an advertising article of manufacture of this kind, 35 means of wide area on the clips to ride against the peripheral edge of the disc, and in such a manner as to prevent rocking of the clip, especially when it is moved along the edge.

40 A further purpose is to provide, in a device of this kind, means consisting of a milling or ridges on the shoulder or rib extending radially, in conjunction with which a lug caused to be formed by an indenture in the clip, so as to hold the clip in various adjusted positions.

It is to be understood that the particulars herein given are in no way limitative, and that while still keeping within the scope of 50 the invention, any desired modification of

details and proportions may be made in the construction of the appliance according to circumstances.

The invention comprises further features and combination of parts to be hereinafter set forth, shown in the drawings and claimed.

In the drawings:—

Figure 1 is a view showing the improved telephone call counting device as applied to the mouth piece of a telephone transmitter.

Figure 2 is a sectional view on line 2—2 of Figure 1.

Figure 3 is a view in elevation of the opposite side of the disc.

Figure 4 shows a group of views of modified forms of discs, showing projections from the edge of the disc for additional advertisements.

Referring to the drawings, 1 identifies a disc, which may be any diameter and of any thickness and constructed of any suitable material, such as pressed paper pulp, paralyn, celluloid, bakelite, etc.

This disc has a central opening 2, of a suitable diameter for the reception of the screw extension 3 of the mouth piece of a telephone transmitter 5, the screw extension engaging into a threaded socket 6 of the telephone transmitter casing, and when the mouth is screwed home tight, the disc is secured between a shoulder 7 of the mouth piece and the marginal face of the transmitter casing adjacent the socket, thereby holding the disc or card securely in place.

Obviously the larger the diameter of the disc, the more space on the front face of the disc is provided for advertising matter.

Adjacent the marginal edge of the disc a rib or shoulder 8 is provided, on the opposite face of which a plurality of numbers 9, say for instance from 1 to 55, are applied, either by stamping, dyeing or otherwise affixed.

A clip 10 is provided, which may be made of any material, for example aluminum, celluloid, paralyn, etc. This clip comprises a body 11, which may be any shape, preferably consisting of a semi-circular portion 12 and a rectangular portion 13. This rectangular portion 13 engages over the face of the shoulder 8 and under its edge 15 and in cooperation

with a shoulder 14 formed at a point between the semi-circular portion and the rectangular portion, so as to retain the clip on the disc, there being a tongue 16 projecting from the marginal curvature of the semi-circular portion 12 to overlie the face of the disc having the numerals from 1 to 55 inclusive. This tongue 16 insures retaining the clip on the disc.

19 The forming of the clip more or less in an elongated form, that is from *a* to *b* with the shoulder 14 riding on the peripheral edge of the disc 1, prevents the clip from rocking excessively when it is in the act of being moved on the disc.

20 The tongue 16 performs the additional function of overlying any one of the numbers. For example the numbers start at the top and are arranged in consecutive order and in a circular direction as shown and end with 55 at the top. In other words the numbers start and end at the top of the disc, and the clip is designed to be moved toward the right. As a telephone call is completed, and not until 25 then, the party making the call moves the clip to cover number 1. If the party makes a number of calls, say five, six or seven, one after the other, the party would move the clip to cover number 8 and then when the ninth call 30 is made the clip is moved to cover the number 9 and so on around the entire peripheral edge of the disc. If this telephone call counting device is installed in an establishment where a number of calls are made during a month 35 and the clip has been moved around the disc one complete circuit, fifty-five calls may be entered in a book, after which the clip may start on its second circuit.

40 The rectangular portion 13 of the clip has an indenture 17 which causes a projection 18 on the opposite part of the rectangular portion, designed to engage with the milled surface 19 of the rib or shoulder 8, the purpose being to retain the clip in different adjusted 45 positions, as it is moved to cover the respective numbers.

45 Either face of the disc may be used for advertising matter, though it may be preferable to use the front face of the disc for other 50 data, such as directions as to how to use the counting device and how to apply it to the telephone.

55 In Figure 4 there is disclosed a group of views of modified shapes of discs 1. In one view of Figure 4 an elliptical disc 20 is disclosed. In the second, third, fourth and fifth views of Figure 4 the various discs 21, 22, 23 and 24 are provided with projections 25, 26, 27 and 28, the opposite faces of which provide 60 for additional advertising matter. In using the clip on the elliptical disc 20, it is mounted to move around the peripheral arcuate edge of the disc, and since the disc is of such shape a substantial amount of advertising space is 65 afforded. In using the other discs of Figure

4, the extensions or projections are disposed at the top of the disc, and the clip starts at the right hand side of each projection and travels around to the left hand side, the numbers being arranged accordingly.

70 The invention having been set forth, what is claimed is:

1. A telephone call counting device comprising a disc body adapted for engagement with a supporting piece of a telephone, said body having one face adjacent the peripheral edge provided with a series of numbers arranged in a circle, a clip conforming to and movable around the peripheral edge of the disc body, and provided with a tongue adapted to cover one number at a time thereby counting the calls as executed, and cooperative means associated with the clip and the marginal portion of the disc body for retaining the clip movable adjacent the peripheral edge.

75 2. A telephone call counting device comprising a disc body adapted for support on the mouth piece of a telephone transmitter, said body having one face adjacent the peripheral edge provided with a series of numbers arranged in a circle, a clip movable around the peripheral edge of the disc body, having a tongue adapted to cover one number at a time thereby counting the calls as executed, and cooperative means associated with the clip and the marginal portion of the disc body, for retaining the clip movable adjacent the peripheral edge, and means to prevent 80 rocking of the clip in a direction circular of the disc body.

85 In testimony whereof he affixes his signature.

JOSEPH J. SHERIDAN.
